UNITED STATES PATENT OFFICE.

WILLIAM HARDY, OF PHILADELPHIA, PENNSYLVANIA, ASSIGNOR TO JOHN BROMLEY AND EDWARD BROMLEY, COPARTNERS, TRADING AS JOHN BROMLEY & SONS, OF PHILADELPHIA, PENNSYLVANIA.

DESIGN FOR A LACE CURTAIN.

No. 39,020.

Specification for Design.

Patented Jan. 14, 1908.

Application filed December 7, 1907. Serial No. 405,621. Term of patent 3½ years.

To all whom it may concern:

Be it known that I, WILLIAM HARDY, a citizen of the United States, residing in the city of Philadelphia, State of Pennsylvania, have invented a certain new, original, and ornamental Design for a Lace Curtain, of which the following is a specification, reference being had to the accompanying drawings, forming a part thereof, whereon is shown sufficient of a curtain to illustrate all the features of the design.

I claim:

The ornamental design for a lace curtain as shown.

WILLIAM HARDY.
